UNITED STATES PATENT OFFICE.

MERRILL H. TERRY, OF COLUMBUS, OHIO.

LANTERN.

Application filed July 5, 1921. Serial No. 482,409.

To all whom it may concern:

Be it known that I, MERRILL H. TERRY, a citizen of the United States, residing at Columbus, in the county of Franklin and State 5 of Ohio, have invented a certain new and useful Improvement in Lanterns, of which the following is a specification.

The object of this invention is to provide a lantern with means whereby it may be 10 easily manipulated to show either one of two kinds of light as for example white and red or white and green and at the same time keep the glass for showing the added color clean and free from a deposit of smoke. 15 Other objects will appear from the following disclosure.

The invention is embodied in the example herein shown and described, the feature of novelty being finally claimed.

20 In the accompanying drawing—

Figure 1 is mainly a central vertical section on the line II—II Fig. 2 through the structure for changing the color of the light.

Fig. 2 is a plan view.

25 In the views 5 designates the cage, guard or frame, the ring 6 in which the fountain 7 with its burner 8 is removably hung. The ring 6 is provided with several horizontal spider arms 6^a that support two metal concentric cylinders 9 and 10. The cylinders 30 9 and 10 are spaced apart to receive a cylinder 11 of transparent glass colored as desired, as for example red or green. On opposite sides of the cylinder 11 and within 35 the cylinders 9 and 10 are secured cylinders of fabric 12 and 13 preferably of felt or other good wiping material. One side of the glass cylinder is provided with a toothed rack 14 of metal suitably secured thereto, 40 said rack being engaged by a small gear 15 on a shaft 16 having a turning head 17 externally of the ring 6 so that the glass cyl-

inder can be raised and lowered when desired. When a colored light is to be shown the glass cylinder is raised as shown in 45 broken lines Fig. 1.

The outer cylinder of fabric is slotted to permit the travel of the rack and all the cylinders are slotted as shown at 18 to permit the insertion and withdrawal of the usual 50 lamp wick operating shaft 20. The interior wiper cylinder of fabric is the more important and the exterior wiper can be omitted.

It will be observed that with this construction when the colored cylinder is raised 55 and lowered in ordinary operation it is wiped by the fabric cylinders and thus kept clear of smoke deposit. It will also be observed that the fount and burner can be removed without removing the colored glass 60 and its container.

The forms of the parts can be changed without departing from the gist of the invention as claimed.

What I claim is:

1. In a lantern, the combination with the fount receiving ring, of a pair of spaced concentric cylinders mounted on said ring, a cylindrical color screen between said concentric cylinders, a stationary wiper cylinder 70 of fabric for the inner side of said color screen and means for raising and lowering the color screen in the direction of its axis.

2. In a lantern, the combination with the fount receiving ring, of a pair of 75 spaced concentric cylinders mounted on said ring, a cylindrical color screen between said concentric cylinders, stationary wipers consisting of cylinders of fabric for the inner and outer sides of the 80 color screen and means for raising and lowering the color screen in the direction of its axis.

MERRILL H. TERRY.
